UNITED STATES PATENT OFFICE.

CHARLES D. ORCUTT, OF DAYTON, OHIO.

DESIGN FOR A STOOL.

SPECIFICATION forming part of Design No. 36,263, dated March 31, 1903.

Application filed February 20, 1903. Serial No. 144,340. Term of patent 3½ years.

To all whom it may concern:

Be it known that I, CHARLES D. ORCUTT, a citizen of the United States, residing at Dayton, in the county of Montgomery and State of Ohio, have invented a certain new, original, and ornamental Design for a Stool; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 The drawing is a perspective view of a stool, showing my new design.

As shown in the drawing, the leading or material features of my design consist in the specific ornamentations of the leg and the 20 skirting, the latter lying along the lower portion of the stool between the legs, and also the upholstered part of the stool, which consists in a series of individual mounds throughout the surface of said upholstered part. The 25 lower portion 1 of the leg is plain, with the exception of the extreme lower end thereof, which is provided with surface ornamentations of more or less irregular forms. The upper portion of the leg is considerably 30 broader than the lower portion and is provided with a series of ornamentations 2, which consist of scrollwork that gradually increases in its outspreading form as it approaches the top of the leg. The ornamentations lying 35 between this scrollwork consist of a series of circular figures 3, which are graduated as they

extend upwardly on the surface of the leg; the uppermost one of said circular figures 3 being the largest of the series. Above this series of circular figures and lying between 40 the scrollwork on the extreme upper end of the leg is an ornamental figure 4, which combines with the scrollwork and the other ornamentations described to present a homogeneous blending of ornamentations. Assembled 45 or associated with this character of ornamentations are the ornamental features of the skirting, which extend around the lower edge of the stool and consist of a series of scrolls 5, the enlarged ends of each of said series 50 curving in opposite directions and two of said series of scrollwork lying between a leg of the stool and a center figure 8. The last-named figure is inclosed between the curved ends of two of the scrolls 5, and the bottom of said 55 figure terminates in a circular figure 7, the whole presenting a series of scrollwork which joins the central figure 8. The upholstered part of the stool consists of a series of mound-like surfaces, between which and the skirting 60 there is a plain surface 10.

Having described my invention, what I claim, and desire to secure by Letters Patent, is—

The ornamental design for a stool as herein shown and described.

In testimony whereof I affix my signature in presence of two witnesses.

CHARLES D. ORCUTT.
